JOSEPH E. LEWIS, OF BALTIMORE, MARYLAND.

TUBE-COILING MACHINE.

1,075,045.

Specification of Letters Patent.

Patented Oct. 7, 1913.

Application filed December 5, 1912. Serial No. 735,048.

To all whom it may concern:

Be it known that I, JOSEPH E. LEWIS, a citizen of the United States, and a resident of Baltimore city, in the State of Maryland, have invented an Improvement in 5 Tube-Coiling Machines, of which the following is a specification.

This invention relates to that class of tube-coiling machines wherein the tube is wound upon a spirally grooved former, but 10 may be used for bending generally.

My machine embodies certain improvements which result in the following advantages: (a) the work is done much more rapidly than heretofore, thus greatly reducing the cost; (b) perfect coils are made without the use of any filling material in the tube; (c) coils may be wound to form spirals of smaller diameter than by the 20 usual method, and this result is accomplished without collapsing or wrinkling the tubes; (d) the metal is properly worked or stretched in the bending process, thereby imparting to the same a desirable degree of hardness or 25 temper, so that the finished coils are not easily dented or distorted by subsequent handling.

The details of construction, arrangement, and operation of the parts composing the 30 machine are as hereinafter described, and illustrated in the accompanying drawings, in which—

Figure 1 is a plan view of the machine as in actual operation. Fig. 2 is a rear elevation of the same. Fig. 3 is a longitudinal section on the line 3—3 of Fig. 1. Fig. 4 is a vertical cross section of the spirally grooved former, together with a longitudinal section of a tube being wound thereon 40 with a mandrel inclosed and shown in side elevation. Fig. 5 is an enlarged cross section on the line 5—5 of Fig. 3. Fig. 6 is a sectional view similar to Fig. 4, save that a portion of the flexible mandrel is shown 45 in cross section. Fig. 7 is in part a plan view and in part a cross section of the flexible mandrel. Fig. 8 is a side view of the same with two extra parts shown. Figs. 9 and 10 are different sections of a modified 50 form of flexible mandrel, the same being adapted for forming spirals which are rectangular in cross section, Fig. 9 being a section on the line 9—9 of Fig. 10, the same being at right angles to the section shown 55 in Fig. 10.

Referring in the first instance to Figs. 1

and 4, the letter α indicates a metal tube which is being wound on a horizontal spirally grooved former 1 having at one end a flanged radial head 1^a, which, in practice, is bolted to the rotatable headstock of a lathe or to the rotatable head of any machine suitable for the purpose, it being understood that the former may be rotated in one direction or the other as required, first, for winding on the tube and forming a coil, and, second, discharging the coil thus produced. The end of the former opposite the head 1^a is provided with an eccentric screw clamp 2 which serves for securing one end of the tube α at the beginning of the coiling operation. What may be termed a carriage or tube-carrier, which supports the tube while being fed to, and wound upon, the former 1, is composed of a 60 metal frame 3 formed of a plate bent at several angles so as to inclose or surround the former, as shown in Figs. 1 and 3. The same is provided with a series of set-screws 4, 5, 6, and 7 which pass through the frame 70 3 and whose rounded points enter, and are adapted to travel in, the spiral groove of the former, by which the carriage is caused to travel automatically forward and backward on the former, as required for coiling 75 the tube about the former in the first instance and discharging the tube coil therefrom when completed. The screws are provided with jam or set nuts, as shown, for locking them in any adjustment relative to 80 the bottom of the spiral groove. On the longer arm 3^a of the rectangular frame 3 there is supported a grooved bar or "shoe" 8, the same being pivoted at 8^a at one side of the frame, as shown in Figs. 3 and 5. This 85 bar has a longitudinal groove in its upper side in which the tube α is adapted to slide, and a V-shaped bar 9 is bolted to the rear end of the shoe and forms an extension support for the mandrel. The rear portion of 90 this mandrel holder is supported by a one-wheel truck 10 which is adapted to travel on a horizontal, transverse rail 11 whose ends are supported by vertical posts 12. As shown in Figs. 1 and 2, a counterweight 105 13 is connected by a rope 14 with the V-shaped mandrel holder 9, the rope running over a pulley 15 fixed at the end of the track 11 and serving a purpose which will be presently explained. In addition to their 110 general functions, each of the several screws 4, 5, 6, and 7 has a function of its own, as

follows: The screw 4 opposes the effect of the counterweight 13 by holding the carriage 3, the shoe 8, and the mandrel holder 9 at the proper angle, as these parts travel 5 together forward and backward. It also serves as a micrometer adjustment of the angularity of the shoe 8 as hereinafter described. The screw 5 serves to regulate the pressure on the tube in the bending or 10 coiling process by drawing the shoe 8 up against the former 1. The screw 6 serves as a bearing point, which in conjunction with the shoe 8 opposes the screw 5 and causes the shoe to bear properly on the 15 former 1. Finally, the screw 7 takes up the thrust due to the pull on the tube α during the coiling process. The lower arm or extension 3^a of the rectangular frame 3 has an arc slot 16 (see Fig. 1) and the clamping 20 bolt 8^a which passes through said slot enables the correct angle of the shoe relative to the former to be found experimentally and the shoe to be securely clamped at the required angle on the frame. This angle is 25 indicated in Fig. 1. In forming the spiral tube coil, I employ a flexible mandrel whose construction in the case of a tube which is cylindrical in cross section is as shown in Figs. 4, 6, 7, and 8, and which will be 30 presently described in detail. The body 17 of the mandrel is provided with an extension rod 18 whose rear end is secured to a lug 19 (see Figs. 1 and 3) whereby the mandrel is held in the tube α and in proper position 35 with reference to the initial bending point of the tube which, as indicated in Figs. 4 and 5, is directly below the former 1.

From the foregoing description, it will now be understood that the method of making a pipe coil or spiral is as follows: First, 40 a straight tube of the required length is placed over the mandrel and extension rod of the same, and the forward end of the tube is secured to one end of the former 1 by 45 means of the clamp 2. The carriage having been duly adjusted in the required position or at the required angle relative to the former is first of all placed in its initial position at the one end of the former, with the 50 shoe 8 engaging the tube at the beginning of the spiral groove. The former is then caused to rotate to the right or in the direction of the arrow in Fig. 4, so that the shoe 8 and the carriage or frame to which it is 55 attached travel along the former 1 with the groove of the shoe in register with the groove in the former whose rotation draws the tube off the mandrel and its extension rod and winds it into the groove of the former as it 60 leaves the mandrel. The metal is compressed between the mandrel stem or body on the inside and the former 1 and shoe 8 on the outside, so that it is stretched or drawn as will be readily understood. The amount of this 65 drawing action may be regulated at will by

putting more or less tension on the adjusting screw 5, as already described. When the carriage has reached the head 1^a of the former 1, the coil is completed, and may then be removed. For this purpose, the clamp 2 is released, and the former 1 is caused to rotate in the opposite direction, so that the carriage with all the attachments travels back to its initial position and at the same time automatically pushes the coil of the former 1 by reason of its unscrewing from the groove in the latter. Another tube is then placed on the mandrel and the process repeated. As before stated, in the coiling operation the spirally grooved former 1 rotates on its axis and the carriage with its attachments travels along the former in a plane parallel to this axis, the motion being similar to that of a nut when held from turning and consequently compelled to travel along a rotating bolt. It is also obvious that the principle is the same if the nut be entirely stationary and the bolt be made to travel backward and forward through the nut as the bolt is rotated. I therefore do no desire to limit my claim to a machine having a rotating spirally grooved former and a carriage traveling thereon, since it is within the scope or principle of my invention that, by securing the carriage, the bending shoe, the mandrel holder, and mandrel in fixed position and allowing the former 1 to travel backward and forward with reference to the carriage, the same result may be secured.

In this class of machines, the function of a mandrel is to support the walls of the flexible tube or pipe during the bending or coiling process, and especially at the point of initial bending as well as at a series of other points in the tube adjacent to and beyond the point of initial bending. In bending or coiling tubes having very thin walls, especially when it is desired to make the bends of a very short radius, there is of course a great tendency of the metal to wrinkle or buckle on the inside of the curve and to flatten or collapse at the outside of the curve. I have invented a special form of flexible mandrel which enables this operation to be performed without difficulty and produces bends of full rounded cross section throughout. A special feature of the flexible portion of the mandrel is the construction of the same of parts whereby the several points of support of the tube while being bent are located so close together that the walls of the tube cannot become distorted between them. I thus produce a superior flexible mandrel which obviates the danger of tubes wrinkling or flattening, however thin the walls or short the radius of the bend. The special novel feature of my construction of mandrel is the provision of a series of bodies or parts which are cut away

and recessed on one side to adapt them to conform to and partially inclose an adjacent part or body, the several parts or bodies being held in intimate contact by means of 5 links or other devices which allow them to swivel or turn on each other as required to conform to curvature of the tube which is being bent.

In the form of mandrel illustrated in Figs. 10 6, 7 and 8, the forward end of the stem or main body of the mandrel is rounded hemispherically and two parts or bodies 20 and 21 are flexibly connected therewith and with each other by means of links 22 and 23. The 15 parts or bodies 20 and 21 are spherical save that they are cut away or truncated on one side and a cup-shaped cavity is formed in such flattened side, the same being adapted to receive a segmental portion of the adjacent body, as will be readily understood by reference to Fig. 7. Two parallel duplicate links 22 flexibly connect the stem 17 with the first or adjacent spherical body 20 and the latter is in turn connected by a single 25 link 23 with the forward or outermost body 21, the links being in each case secured to pivots 24 which traverse the respective parts 17, 20 and 21, as shown.

It will be understood by reference to Figs. 30 6, 7 and 8 that the links 22 and 23 are arranged in fan-shaped slots in the stem 17 and body 20 which permits the required lateral movement of the links during the bending operation. It will be understood in this 35 connection that I may employ a chain or a flexible cord or wire for connecting the several parts 17, 20 and 21, the main feature being a suitable flexible connection of the parts with adjustment of their transverse 40 axes as near each other as practicable in order to avoid buckling or otherwise distorting the tube.

In Figs. 9 and 10, I illustrate a modification, that is to say, cylindrical parts 17^a, 20^a, 45 and 21^a, this form being particularly adapted and intended for use in bending tubes that are rectangular in cross section. The arrangement and connection of the links 22^a and 23^a are in essentials similar to that employed in the case of the spherical bodies before described.

It will be seen that in any case, the flexible parts of the mandrel must be so shaped that the cross section at right angles to the 55 axis of the tube shall be of the same shape as the cross section of the tube itself, and the cross section in line with the axis of the tube and with the plane of the bend shall be a circle intersected by another circle of the same size. This refers to the primary, or fundamental, form of the bodies. Their cross section is, of course, modified internally to such an extent as may be desirable or necessary for the fan-shaped slots, etc., 60 in linking the parts together. Such internal

modifications, however, do not interfere with the external contour or change the essential form of the bodies.

What I claim is:—

1. In a tube-bending machine, in combination, a spirally grooved rotatable former, a metallic frame inclosing said former and arranged to travel backward and forward on said former, it being automatically propelled by engagement with the groove in the former, a grooved bending shoe pivoted on one side of said frame, the groove in the shoe always registering with the groove in the former at the bending point, and a mandrel attached to and traveling with the bending shoe, as described. 70

2. In a tube-bending machine, in combination, a spirally grooved former, a metallic frame inclosing said former on four sides and provided with adjustable bearing screws 85 disposed to engage the spiral groove in said former, a grooved bending shoe pivoted on one side of the frame, and means to adjust said shoe to the proper angle and clamp it securely in position, and a mandrel and 90 mandrel holder.

3. In a tube-bending machine, in combination, a spirally grooved former, a metallic carriage applied to said former and automatically guided and controlled by it, a 95 grooved bending shoe pivoted beneath and on one side of said carriage and thus adapted for lateral adjustment relative to the former, and a flexible mandrel supported on said shoe, as described. 100

4. In a tube-bending machine, in combination, a spirally grooved rotatable former, a grooved bending shoe held adjacent to the former at the bending point where the tube receives its initial bend, a mandrel holder 105 attached to said shoe and movable with the same, and means causing relative motion between the bending shoe and the former in a plane parallel to the surface of such former, as described. 110

5. In a tube-bending machine, the combination with a spirally grooved rotatable former, of a carriage adapted to traverse said former, the same comprising a frame that surrounds the former, adjustable means 115 connected with said frame and bearing in the groove and adapted to travel in the same, a grooved tube guide pivoted on said frame, and means for securing it at any desired lateral inclination to the axis of the former, 120 as described.

6. In a tube-bending machine, the combination with a spirally grooved rotatable former, of a carriage adapted to traverse said former, the same comprising a frame 125 that surrounds the former, adjusting set-screws passing through the frame and bearing in the groove at several points and adapted to travel in the groove, a tube guide pivoted on the lower portion of said frame 130

and extending beneath the former, means for securing it at any desired lateral inclination to the axis of the former, a device for clamping it in lateral adjustment, a counterweight connected with the rear portion of the tube

guide and tending to draw the same laterally, and means for supporting the rear end

of the tube guide while permitting lateral traverse of the same, as described.
